FIGURINE CONSTITUTING A RING HOLDER

George V. Pisani, Detroit, Mich., assignor to Gerard Industries, Toledo, Ohio, a corporation of Ohio

Application December 11, 1953, Serial No. 28,029

Term of patent 3½ years

(Cl. D86—9)

To all whom it may concern:

Be it known that I, George V. Pisani, a citizen of the United States and a resident of Detroit, Wayne County, Michigan, have invented a new, original, and ornamental Design for a Figurine Constituting a Ring Holder, of which the following is a specification, reference being had to the accompanying drawing, forming a part thereof.

In the drawing:

I claim:

The ornamental design for a figurine constituting a ring holder, as shown.
